DESIGN FOR A REFRIGERATING UNIT, FOR RECEIVING AND STORING FROZEN CUSTARD OR THE LIKE

Charles Erickson and Erick Spellman,
New York, N. Y.

Substitute for abandoned application Serial No.
82,599, January 25, 1939. This application
May 15, 1940, Serial No. 92,402.

Term of patent 7 years

To all whom it may concern:

Be it known that we, Charles Erickson and Erick Spellman, both citizens of the United States of America, residing at New York, in the county of the Bronx, in the city and State of New York, have invented a new, original, and ornamental Design for Refrigerating Unit, for Receiving and Storing Frozen Custard or the like, of which the following is a specification, reference being had to the accompanying drawing, forming part hereof.

This is a substitute for our prior application, Serial No. D-82,599, filed Jan. 25, 1939.

Fig. 1 is a perspective view of a refrigerating unit, for receiving and storing frozen custard or the like, showing our new design, the top tray portion being shown in disassembled relation with respect to the remainder of the article in order to show the configuration of the upper portion thereof;

Fig. 2 is a side elevational view of the article, as seen from the left of Fig. 1, the top tray portion being shown in its assembled relation with the remainder of the article; and

Fig. 3 is a front elevational view of the same article.

We claim:

The ornamental design for a refrigerating unit, for receiving and storing frozen custard or the like, as shown and described.

CHARLES ERICKSON.
ERICK SPELLMAN.
